UNITED STATES PATENT OFFICE.

MAX ROGLER, OF RATINGEN, GERMANY.

APPARATUS FOR TAPPING LIQUIDS SUCH AS PAINT FROM RECEPTACLES.

Application filed July 10, 1924. Serial No. 725,311.

To all whom it may concern:

Be it known that I, MAX ROGLER, a citizen of the German Republic, and residing at Ratingen, Germany, have invented certain new and useful Improvements in Apparatus for Tapping Liquids Such as Paint from Receptacles (for which applications for patent have been filed in Germany October 26, 1922, and August 20, 1923), of which the following is a specification.

My invention relates to improvements in apparatus for tapping liquids such as paint from receptacles, and the object of the improvements is to provide an apparatus by means of which the paint is stirred before being taken from the receptacle, so that the deposit formed at the bottom is first mixed with the body of the liquid and liquid of homogeneous composition is withdrawn from the receptacle and a waste of liquid deposited at the bottom is avoided. With this object in view I provide apparatus for withdrawing liquid by means of which the liquid is stirred a certain length of time before it is discharged from the receptacle.

For the purpose of explaining the invention two examples embodying the same have been shown in the accompanying drawings in which the same reference characters have been used in all the views to indicate corresponding parts. In said drawings,

Fig. 1, is an elevation partly in section showing the apparatus,

Fig. 2, is a sectional plan view taken on the line 2—2 of Fig. 1 and showing the stirring means,

Fig. 3, is a sectional elevation of the stirring means taken on the line 3—3 of Fig. 1,

Fig. 4, is an elevation partly in section showing a modification, and

Fig. 5, is a section taken on the line 5—5 of Fig. 4 and showing the rotary pump.

In describing the invention reference will be made to an apparatus for withdrawing paint from a receptacle. But I wish it to be understood that my invention is not limited to such use.

As shown in Figs. 1 to 3, my improved apparatus is mounted on a plate 1 adapted to be placed on and secured to the open top of a receptacle 2 containing the paint. Any preferred means may be provided for fixing the plate in position. To show what may be done the plate is formed with arms 40 re-

ceiving clamping screws 3 adapted to engage the receptacle from the side thereof. It will be understood that the type of the said fixing means and the size of the plate 1 are different according to the size and form of the receptacle. The plate 1 is fixed to the receptacle so as to close the same in an air tight manner and to prevent loss of paint and spoiling thereof by vaporization and access of air and impurities.

To the plate 1 a plate 41 is secured which is provided with a vertical bearing 4 disposed axially of the receptacle and providing a guide for a tubular shaft 5 passed downwardly therethrough and into the receptacle to the bottom thereof where it shows a conical end engaging the bottom and providing an additional support for holding the same axially within the receptacle. The bottom part of the shaft 5 carries a helical stirring member 6 and a transverse arm 7 provided with bottom stirring members 8, 9 and 10. As shown the members 8 are in the form of springs projecting downwardly and rearwardly from the arm 7 and into position for engaging the bottom of the receptacle, the members 9 are in the form of scratching members jointed to each other, and the members 10 consist of upwardly directed sheet metal plates adapted to retard the operation of the apparatus while stirring the paint. The shaft 5 carries a collar 42 fixed thereto by means of a screw 12 and adapted to be set in different positions for adjusting the shaft 5 in vertical position and accommodating the same to receptacles of different heights. The shaft 5 is adapted to be rotated by means of a bevel gearing 13, 13, a shaft 43 mounted in bearings 44 and 45 rising from the plate 41 and a crank 14 secured to the shaft 43.

Within the tubular shaft 5 there is a non-rotatable pipe 15 secured at its top end by means of a screw 17 to an arm 18 projecting laterally from an upright 46 rising from the plate 41, and it is adapted to be adjusted in vertical direction by means of the screw 17 according to the height of the receptacle. At its bottom the pipe 15 shows a check valve 47 and a plunger 16 provided with a check valve 48 and connected with a rod 19, said parts providing a pump for taking paint from the receptacle. The connecting rod 19 is adjustably connected to a crank pin 48 provided on a crank disk 21 the shaft 49

of which is mounted in the upright 46. The crank disk is adapted to be rotated by means of a bevel gearing 22, a shaft 23 and spur gears 25 from the tubular shaft 5. Normally the bevel gearing 22 is disconnected from the shaft 23 and it is adapted to be connected therewith by means of a clutch 24, 28, the member 28 being adapted to be shifted into coupling position by means of a centrifugal governor 49 provided with arms 27 engaging a disk 50 carrying the clutch member 28. The governor is confined within a casing 26.

The operation of the apparatus is as follows: For taking paint from the apparatus the crank 14 is turned and rotary movement is imparted to the shaft 5 and the stirring members 8, 9 and 10. Such rotary movement is transmitted through the gears 25 to the shaft 23 and the governor 49. After the paint has been stirred a certain length of time the velocity of the apparatus is such that the governor shifts the clutch member 28 into coupling engagement with the clutch member 24, whereupon the pump 16 is operated for raising paint through the pipe 15, which paint flows through a rockable gutter 20. If the velocity of the operation is insufficient to insure proper stirring of the paint, or when stopping the pumping altogether, the governor 49 permits the member 28 to be disengaged from the member 24, whereupon the operation of the pump is interrupted. By enclosing the governor within the casing 26 the attendant is prevented from closing the clutch 24, 28 by hand for taking paint from the receptacle without stirring the same.

In the modification shown in Figs. 4 and 5 the clutch 24, 28 and the governor 49 are dispensed with, and the pump is always in connection with the stirring and driving mechanism, stirring of the paint being insured by providing a pump, such as a centrifugal pump, which raises the paint only after the mechanism has assumed a certain velocity and the paint has become sufficiently fluent.

At its bottom end the pipe 15 is formed with a casing 30 having a discharge passage 35 provided with a bottom plate 36 for directing the liquid upwardly and into the pipe 15. Within the pipe there is a rotary shaft 32 carrying blades 31 at its bottom end, said casing, passage, blades and shaft providing a centrifugal pump taking the liquid from the receptacle 2 and raising the same through the pipe 15. To the top end of the shaft 32 a pinion 33 is secured which is in mesh with a large gear 34 keyed to the shaft 23.

The shafts 5 and 23 are driven from the crank 14 in the same way as has been described with reference to Figs. 1 to 3. For taking paint from the receptacle the crank

14 is turned and the shafts 5 and 23 are rotated. At first the paint is merely stirred and not raised by the pump 31. As the paint becomes fluent by stirring the resistance opposed to the stirring mechanism is reduced and the speed of the mechanism and the pump is increased, until it is sufficient to raise paint through the pipe 15. Should the attendant fail to turn the crank 14 fast enough the discharge of paint is interrupted, so that the paint can be taken from the receptacle only after being sufficiently stirred.

While in describing the invention reference has been made to particular examples embodying the same I wish it to be understood that my invention is not limited to the constructions shown in the drawing, and that various changes may be made in the general arrangement of the apparatus and the construction of its parts without departing from the invention.

I claim:

1. In an apparatus of the class described, the combination, with tapping means, and stirring means, of common operating means for successively actuating said tapping and stirring means.

2. In an apparatus of the class described, the combination, with a pump, and stirring means, of common operating means for said pump and stirring means including means for initiating the operation of the pump subsequent to the starting of the stirring means.

3. In an apparatus of the class described, the combination, with stirring means, and operating means therefor, of tapping means adapted to be operated by said operating means, and means for rendering the latter operative relative to said tapping means after said operating means have built up speed with said stirring means.

4. In an apparatus of the class described, the combination, with stirring means, and operating means therefor, of tapping means adapted to be operated by said operating means, and means operative after said operating means have built up speed to connect said operating means and tapping means.

5. In an apparatus of the class described, the combination, with stirring means, and operating means therefor, of a pump adapted to be operated by said operating means, and a clutch operative after said operating means have built up speed for connecting the pump to said operating means.

6. In an apparatus of the class described, the combination, with stirring means, and operating means therefor, of a pump adapted to be operated by said operating means, and automatic means operative after starting the operating means to connect said pump with said operating means.

7. In an apparatus of the class described, the combination, with stirring means, and

- operating means therefor, of a pump adapted to be operated by said operating means, and automatic means operative after starting the operating means to connect said 5 pump with said operating means and to disconnect the same when the stirring operation is discontinued.
8. In an apparatus of the class described, the combination, with stirring means, and 10 operating means therefor, of a pump adapted to be operated by said operating means, and means operable upon a predetermined speed of said stirring means to connect said pump with said operating means.
15. 9. In an apparatus of the class described, the combination, with a plate adapted to be fixed to the top of a receptacle for closing the same, tapping means, and stirring means, of common operating means for said tapping 20 and stirring means, said tapping, stirring and operating means being mounted on said plate and speed responsive means for connecting the tapping means following the starting of the stirring means.
25. 10. In an apparatus of the class described, the combination, with tapping means, and stirring means comprising a rotary shaft, a helical member, a radial arm and linked 30 scratching members mounted on said shaft, of common operating means for said tapping and stirring means.
11. In an apparatus of the class described, the combination, with a plate adapted to be fixed to the top of a receptacle for closing 35 the same, and tapping means, and stirring means, of common operating means for said tapping and stirring means, said tapping, stirring and operating means being mounted on said plate and said stirring means being 40 vertically adjustable relatively to said plate.
12. In an apparatus of the class described,
- the combination, with a tubular shaft, and stirring means mounted on said shaft, of a pump within said shaft and having its discharge through the same, and operating 45 means common to said shaft and pump.
13. In combination with a pump for dispensing a liquid which should thoroughly be agitated before being dispensed, of means for agitating the liquid, and means actuated by 50 the agitating means for automatically operating the pump when the liquid has been so agitated.
14. In combination with stirring means, operating means therefor, a pump, and speed 55 responsive means for connecting the pump to said operating means after the stirring means has reached a predetermined speed and for disconnecting the pump from said operating means when the stirring means 60 falls below said predetermined speed but preliminary to said stirring means coming to rest.
15. In combination with a stirring means, operating means therefor, and dispensing 65 means operable by said operating means, said stirring means comprising a swingingly mounted arm, spring members projecting rearwardly and downwardly from the arm, and a jointed scratching member carried by 70 the outer end of the arm.
16. In combination with a stirring means, operating means therefor, and dispensing means operable by said operating means, said stirring means comprising a swingingly 75 mounted arm, spring members projecting rearwardly and downwardly from the arm, upwardly extending spring members carried by the arm, and a flexible means carried by the outer end of said arm.

In testimony whereof I affix my signature.
MAX ROGLER.
